UNITED STATES PATENT OFFICE.

HENRY L. SCOTT, OF PROVIDENCE, RHODE ISLAND.

TENSION MECHANISM FOR TESTING-MACHINES.

1,219,594.

Specification of Letters Patent. Patented Mar. 20, 1917.

Application filed July 6, 1915. Serial No. 38,071.

To all whom it may concern:

Be it known that I, HENRY L. SCOTT, a citizen of the United States and resident of the city of Providence, in the county of Providence and State of Rhode Island, have invented certain new and useful Improvements in Tension Mechanism for Testing-Machines, of which the following is a specification.

10 This invention relates to tension applying mechanism more particularly adapted for use on testing machines, and the object of this invention is to provide a device of this character that is positive in its tension operation and one whose feeding action may be either manually or automatically reversed.

20 A further object of this invention is to provide means whereby the tension will automatically stop when it has returned to the starting point after an operating stroke.

25 A further object of the invention is to provide means whereby the return stroke will be accelerated over the tension stroke.

30 With these and other objects in view, the invention consists of certain novel features of construction, as will be more fully described, and particularly pointed out in the appended claims.

35 In the accompanying drawings:

Fig. 1—is a side elevation showing a horizontal type of testing machine to which my improved tension operating mechanism is attached.

40 Fig. 2—is a plan view of the tension operating mechanism with the top of its enclosing casing removed.

45 Fig. 3—is a plan view of the casing showing a portion of the operating mechanism removed therefrom to better illustrate a portion of the shifting mechanism.

50 Fig. 4—is a sectional end view on line 4—4 of Fig. 2 illustrating the general arrangement of the gearing whereby the return movement of the screw is accelerated.

Fig. 5—is a detail elevation of the posi-

tive and friction clutches also the yoke and yoke bar for shifting the clutches.

Fig. 6—is a plan view showing a detail of the yoke bar and the two notches to be engaged by the yoke lever.

Fig. 7—is a modification showing another arrangement of the clutch operating mechanism.

Referring to the drawings Fig. 1 illustrates my improved mechanism as applied to a horizontal type of testing machine in which 10 and 11 illustrate the end frames of the machine, which frames are connected by the tie rods 12 and 13. Carriages 14 and 15 are mounted to roll on rails 16. On carriage 14 is mounted the clamp 17 and on carriage 15 the clamp 18, between which clamps the material *a* to be tested is gripped. The carriage 14 is connected through the chain 19 to the hub 20 which is controlled in its rotation by means of weighted arms (not shown) and which is also connected by suitable means to the pointer 21, whereby the tension on the goods being tested is indicated by the position of the pointer on the graduated dial 22. The tension carriage 15 is connected by the non-rotatable endwise movable screw 23 to the tension mechanism, presently described, located in the casing 24 on the frame 10 through which casing this screw passes as shown in Fig. 2.

In order that the endwise movement of this screw may be effected without rotating the same, I have mounted thereon a nut 25, which serves as a bushing to the two driving gears 26 and 27 and to reduce the friction of the thrust or working strain on this screw, I have interposed a ball thrust bearing 28 between the nut 25 and bearing 29.

In order to facilitate the operation of a machine of this character, it is found advisable to provide means whereby the return stroke may be accelerated over that of the working stroke. Therefore to accomplish this, I have made these two gears of different sizes and have arranged to drive them through different sets of mechanism presently described.

Power may be applied to this tension mechanism either by a hand wheel 30 or through tight and loose pulleys 31 to the

2
driving shaft 32 on which shaft is mounted the double clutch member 33 to slide on the usual feather key 34, see Fig. 5. One end of this clutch member is provided with 5 teeth 35 adapted to engage and positively drive the other member of the clutch 36, which second member is loosely mounted on its shaft 32 and to which is connected a bevel gear 37 which meshes with a similar gear 38 keyed to the shaft 39. On the outer portion of this shaft is mounted a small gear 40 adapted to mesh with the large gear 27, whereby when the toothed clutch is thrown into engagement the nut is turned 10 by the large gear 27 to draw the screw outward or to impart to the screw its working stroke. On the opposite end of this clutch member is a cone member 41 which is adapted to engage its corresponding clutch member 42. To this latter member as 15 shown in Fig. 2 is connected a bevel gear 43 which meshes with the pinion 44 mounted on the shaft 45 to which shaft is also connected a large gear 46 which meshes 20 with the nut gear 26, whereby when the cone clutch is in engagement, the nut is driven at a relatively fast speed to return the screw and its clamp to the starting position. It is found in practice that owing 25 to the great strain upon the screw that a positive or toothed shaped clutch is necessary for driving the screw on its operating stroke, but as the work of driving this screw upon its return stroke is very much less 30 than on its operating stroke I have provided a cone shaped clutch 40 and 41 through which this reverse action is imparted.

A further object and essential feature of 40 the cone clutch is that after the tension mechanism is returned to normal the members of the cone clutch are automatically withdrawn from each other requiring but a slight movement to release and free itself 45 and when so released the parts continue to rotate one within the other noiselessly and without the clicking sound of ratchet teeth which is the case when a toothed clutch is employed for this particular purpose.

50 This is quite essential as these machines are often employed in business offices where silent running is demanded.

It is found in practice advisable to provide means whereby this mechanism may 55 be automatically operated to shift the clutches when the carriage reaches a predetermined point in its travel during its working stroke, and to return the carriage to its starting point without attention from 60 the operator. To accomplish this, I have provided a yoke member 47 to engage the clutch member 33 and have connected this yoke to the endwise movable yoke bar 48 which receives its bearing in bosses 49 and 50

in the casing. A spring 51, see Fig. 3, exerts a tension on this bar to move the clutch into reverse position when released and a latch lever 52 pivoted at 53 and under tension of spring 56 is provided with a lip 54 for engaging a notch 55 in this yoke bar to normally hold 70 the same against movement under action of its spring 51. This latch lever 52 has an outwardly extending arm 57. I have also provided a bell crank lever 58 pivoted at 60, one arm of which engages an abutment 75 59 on the yoke bar 48 and the other arm 61 of this lever is provided with an opening 62. In order to operate this mechanism in the casing from any desired point along the machine, I have provided an elongated rod 80 63 which extends along the top of the frame. Its inner end 64 passes through the opening 62 in the arm 61 and abuts against the end 57 of the latch lever 52. On this rod as illustrated in Fig. 1, I have located 85 dogs 65 and 66 which are adapted to be engaged by the ear 67 on the carriage 15, and I have also provided collars 68 and 69 on this rod which are engaged by the arm 70 of the hand lever 71, which is pivoted 90 to the frame at 72. Assuming now that the mechanism is in neutral position which is that illustrated in Fig. 2 and the sample a to be tested is positioned between the 95 clamps 17 and 18. To start the testing operation, I move the handle of the lever 71 downward which draws the rod 63 outward causing the arm 58 of the bell crank lever to move the yoke 47 and throw the positive or toothed clutch into engagement 100 to drive the nut 25 through the gears 40 and 27 to slowly but powerfully draw the tension screw outward. Now as the carriage 15 moves to the right and as soon as it has completed its testing stroke, it engages the dog 65, presses the rod 63 inward causing its end 64 to press against the end 57 of the latch lever 52 withdrawing it 105 from notch 55 and permitting the yoke 47 under tension of the spring pressed yoke bar to disengage the teeth of the positive clutch and move the cone 41 into engagement with its member 42, whereby a much quicker motion is imparted to the screw 110 by means of the differently proportioned 115 gearing, to return the tension elements to the starting point at which time the ear 67 on the carriage 15 engages the dog 66, draws the rod 63 outward and the clutch member 41 out of engagement with this member 42 sufficiently to permit the mechanism to run idle until again manually operated.

In some cases particularly when this mechanism is applied to a vertical machine, 125 it is found more convenient to do away with the lever 71 for operating the tension mechanism and to provide a lever mounted on the

- casing, itself, in such a position as to be handy to operate. To accomplish this, I have provided a lever 72, see Fig. 1, pivoted at 73 on the casing and provided with an arm 74 which engages an endwise movable spindle 75. This spindle passes through the casing, see Fig. 3, and its inner end is provided with a slotted member 76 through which a pin 77 in the lever 61 extends, and a spring 78 presses against a portion 76 of the spindle to normally press it inward, which pressure serves to return the hand lever 72 back to normal as soon as released after performing this operation. In operating this lever when the mechanism is set in a vertical position, the handle is moved forward, which movement as will be seen by the mechanism in Fig. 3 and as above described operates through the yoke to cause the positive clutch members to move the screw through its working stroke, and when the screw is moved a predetermined distance the mechanism is stopped through a movement of the rod 63.
- 25 It is found in practice desirable in some cases to provide means whereby instead of permitting the automatic shift to reverse the action of the machine entirely, to provide means whereby this automatic operation simply stops the machine on its outer stroke as well as on its inward stroke. To accomplish this as illustrated in Fig. 6 a second notch 90 is provided in the bar 48, whereby when the latch 54 is withdrawn 30 from notch 55, it simply permits the yoke bar to move a sufficient distance to disengage the positive clutch when this latch engages the boss 90 and retains the clutch in neutral position.
- 40 In some cases instead of operating through the two bell crank levers illustrated in Fig. 3, I use the construction illustrated in Fig. 7, whereby a wedge 80 is mounted on the endwise movable rod 81 which wedge engages the lever 82 to directly act upon and throw the clutch member 83. In this mechanism when it is desired to start the machine the hand lever 84 is moved into engagement where it is held by the member 85 resting in 45 the notch 86, then as the screw 87 moves inward the arm 88 engages the collar 89 and moves the wedge inward causing the clutch member 83 to move in the opposite direction under tension of the spring, not shown, to 50 reverse the action of the mechanism.
- 55 This invention is not restricted to any of the particular forms of mechanism herein illustrated and described as various modifications may be made without departing from 60 the spirit and scope thereof.
- I claim:
1. In a testing machine, means for gripping the work, a screw connected to the gripper, means operating on the screw for mov-
  - ing the gripper to tension the goods, means for automatically reversing the action of the screw at a predetermined point in the tension stroke, said reversing means being adapted to produce more rapid motion in the reverse than in the direct movement of the screw.
  2. In a testing machine, means for gripping the work, a screw connected to the gripper, means operating on the screw for feeding the gripper to tension the goods, and manually operable means for starting and stopping and reversing the action of the screw, and means including differential gearing for automatically returning said operable means to normal after an operating movement of the machine.
  3. In a testing machine, a tension applying mechanism comprising means for gripping the work, a screw connected to the gripper, means operating on the screw for imparting a feeding movement to the gripper to tension the goods, means for automatically reversing the action of the screw at a predetermined point in the tension stroke, said reversing means being adapted to produce more rapid motion in the reverse than in the direct movement of the machine.
  4. In a testing machine, a tension applying mechanism comprising means for gripping the work, a screw connected to the gripper, means operating on the screw for imparting an endwise feeding movement to the gripper to tension the goods, means for automatically reversing the action of the screw at a predetermined point in the tension stroke, and means for automatically stopping the movement of the gripper at the end of its return stroke.
  5. In a testing machine, a tension applying mechanism comprising means for gripping the work, a screw connected to the gripper, means operating on the screw for imparting a feeding movement to the gripper to tension the goods and means for reversing the action of the screw at a predetermined point in the movement of the gripper, said reversing means being adapted to produce more rapid motion in the reverse than in the direct movement of the screw, and means for stopping the gripper at the end of its return stroke.
  6. In a testing machine, means for gripping the work to be tested, a screw connected to drive the gripper, means operated by the screw for feeding the gripper to tension the goods, a manually operable shipper lever for starting the machine and means for automatically returning said lever to normal after an operating movement of the machine.
  7. In a testing machine, means for gripping the work to be tested, a screw operatively connected to the gripper, means in-

cluding a toothed clutch for positively operating upon the screw to feed the gripper in one direction, and a friction clutch for operating the reverse mechanism.

5 8. In a testing machine, means for gripping the work to be tested, a screw opera-

tively connected to the gripper, a rotatable nut on the screw for drawing the nut in one direction and a friction clutch for reversing the action of the nut and screw.

10

In testimony whereof I affix my signature.

HENRY L. SCOTT.
